[57] **CLAIM**

The ornamental design for a fly swatter, as shown and described.

DESCRIPTION

FIG. 1 is a perspective top view of a fly swatter in accordance with my design;

FIG. 2 is an elevated front end view thereof;

FIG. 3 is a top plan view thereof;

FIG. 4 is a bottom plan view thereof;

FIG. 5 is an elevated rear end view thereof;

FIG. 6 is a left side view thereof; and,

FIG. 7 is a right side view thereof.

The broken line showing of a car and a portion of the handle is for illustrative purposes only and forms no part of the claimed design.
